US00D665740S

(12) **United States Design Patent**
Yamada et al.

(10) **Patent No.:** US D665,740 S
(45) **Date of Patent:** ** Aug. 21, 2012

(54) **COIL COMPONENT**

(75) Inventors: **Satoru Yamada**, Tokyo (JP); **Kazuyuki Kikuchi**, Tokyo (JP)

(73) Assignee: **Sumida Corporation**, Chuo-Ku, Tokyo (JP)

(**) Term: **14 Years**

(21) Appl. No.: **29/408,389**

(22) Filed: **Dec. 12, 2011**

(30) **Foreign Application Priority Data**

Nov. 18, 2011 (JP) D2011-026786

(51) **LOC (9) Cl.** **13-01**

(52) **U.S. Cl.** **D13/117**

(58) **Field of Classification Search** D13/117, D13/101, 118, 133, 179, 183, 199; 123/634; 250/231.12; 336/83, 90, 92, 96, 160, 178, 336/192, 198, 200; D15/5, 199

See application file for complete search history.

(57) **CLAIM**

The ornamental design for a coil component, as shown and described.

DESCRIPTION

FIG. 1 is a front elevational view of a coil component showing our new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a top perspective view thereof; and,

FIG. 8 is a bottom perspective view thereof.

1 Claim, 5 Drawing Sheets

FIG. 1

FIG. 2

FIG. 3

FIG. 4

FIG. 5

FIG. 6

FIG. 7

FIG. 8
